STEAK KNIFE

Irving Harper, New York, N. Y., assignor to Chas. D. Bridgell, Inc., Crisfield, Md., a corporation of Maryland

Application August 1, 1955, Serial No. 37,244

Term of patent 14 years

(Cl. D22—3)

Fig. 1 is a side elevational view of a steak knife showing my new design.

Fig. 2 is a top plan view of the knife shown in Fig. 1.

Figs. 3 and 4 are, respectively, cross sectional views taken on the lines 3-3 and 4-4 of Fig. 1.

I claim:

The ornamental design for a steak knife, as shown.
